UNITED STATES PATENT OFFICE.

JOHN J. DOSSERT, OF NEW YORK, N. Y., ASSIGNOR TO DOSSERT & COMPANY, A CORPORATION OF NEW YORK.

INSULATED COUPLING FOR ELECTRIC CONDUCTORS.

No. 892,411.

Specification of Letters Patent.

Patented July 7, 1908.

Application filed March 8, 1906. Serial No. 304,867.

To all whom it may concern:

Be it known that I, JOHN J. DOSSERT, a citizen of the United States, and resident of New York, county of New York, State of New York, have invented certain new and useful Improvements in Insulated Couplings for Electric Conductors, of which the following is a specification.

My invention relates to couplings for electric conductors, either single or stranded, the object being to provide such couplings in a form convenient for attachment and for handling and also in such form that the completed coupling presents an insulating surface which removes all danger of accident through contact with the metallic portion of the coupling and at the same time presents an attractive appearance.

The invention is applicable to the making of joints in cables or conductors under any ordinary conditions; but it offers special advantages for the purpose of connecting motor leads to the wiring of motor cars. The present method of making these connections is very inconvenient and the act of forming the coupling connection is attended with danger and not infrequently results in accidents more or less serious. Moreover, it takes a long time to make the present connections and cover them with tape, while the cost of the tape itself used and lost in the operation is an item of considerable expense, and the completed coupling is not attractive in appearance.

The invention described herein obviates the difficulties named, as will be seen by reference to the accompanying drawings and the present description thereof.

The drawings represent, in Figure 1, a side view of a metallic coupling together with a longitudinal section of the surrounding insulation; in Fig. 2 a vertical section along the line $x-x$ in Fig. 1; and in Fig. 3 an elevation showing the portions of the insulating covering at one end, together with a modification in a detailed cross-section at the other end. Fig. 4 is a vertical section taken on the line $y-y$ Fig. 1. Figs. 5 and 6 are broken longitudinal sectional views of one end of the coupling showing different forms of packings to make water tight joints.

In the drawings, 1 represents a stranded conductor or cable inclosed in an insulating covering 2. The adjacent ends (not shown) of this cable are connected by a coupler, the

two end pieces of which are shown at 3, 3, and the intermediate connecting member is shown at 4. These couplers are now well-known as to their general character, since the issuance of certain Letters Patent of the United States to me, but the details are generally immaterial, it being only understood that the adjacent ends of the cable enter the end pieces of the coupling, while the metal piece constitutes a connecting element for the said coupling ends whereby electrical continuity is preserved throughout the coupling.

It will be observed that the central portion of the connecting member or element 4 appears in the form of a nut, which may be hexagonal, octagonal, or any other suitable shape, for the application of a tool whereby the same can be turned so as to cause the end pieces and the parts of the coupling to which they are attached to approach each other and make a good electrical and mechanical joint. For this purpose, oppositely threaded screws, 5 and 6, are formed on the hubs or ends of the said central portion, the same cooperating with corresponding screw threads inside the end pieces 3, 3. It is to be noted that the outside surfaces of the said central portion of the member 4 are more remote from the axis than are the surfaces of the end pieces 3, 3. The purpose of this will presently be explained. It is to be further noted that the end pieces 3, 3, themselves are provided with angular surfaces and it is to be remembered that these end pieces may have tools applied to them for forming the connection above described, it being sometimes preferable to apply a steady tool to the member 4 and an operating tool to the end pieces 3, 3, one after the other.

To receive the end pieces 3, 3, the cable or conductor ends are bared, as readily understood, and the said end pieces are slipped over the bared ends of the conductors or cables.

Outside the metallic coupler hereinbefore described, I arrange the sheathing of insulating material consisting of the parts 7 and 8, as shown. In adjusting the entire coupling device, these parts 7 and 8 are first slipped over the insulation 2, 2, on the conductor or cable, and are carried back far enough to allow the parts 3, 3 to be then passed over the ends of the said conductor or cable and the element 4 to be introduced

between the said parts 3, 3. After the metallic portion of the coupler has been suitably adjusted as already described, the parts 7 and 8 of the insulating sheathing are 5 screwed together, one of these parts, as 8, being provided with a male screw, and the other with a female screw, for this purpose. In the form illustrated in Fig. 1, the part 7 is provided with a shoulder, 9, which is 10 adapted to stand on one side of the enlarged portion of the element 4, while the end, 10, of the male screw upon the part 8 stands on the other side of the said element so that when the parts are firmly screwed together 15 the said element is held from excessive longitudinal movement, although it is free to move in a circumferential direction so that there is no danger of a breaking down of the device due to the natural tendency thereof 20 to shift more or less in a radial direction. At the same time, all tendency to separate the parts by longitudinal strain is resisted by the construction shown.

The material selected for the insulating 25 sheathing made up of the parts 7 and 8 may be vulcanite or any other suitable insulating material having sufficient rigidity and the capacity for receiving screw threads, retaining 30 its shape under the conditions to which the sheathing is subjected.

It will be observed that the parts 7 and 8 fit at their outer ends with tolerable tightness over the insulated portions 2, 2. However, in Figs. 3, 5 and 6 I show special means 35 for providing an absolutely water tight connection between the said parts and the covering portions 2, 2. For example, at 11, I illustrate a band of soft rubber which may be inserted in place in such manner that the 40 screwing together of the parts 7 and 8 will compress the inner end of the rubber between the outer end of the part 3 and the inner shoulder 12 on the part 8 or the part 7 as the case may be, it being assumed that both 45 the part 8 and the part 7 are similarly provided with shoulders 12, 12, as illustrated in Fig. 1. Thus, the insulating sheathing composed of the parts 7 and 8 may be made either sufficiently tight for ordinary purposes as shown in Fig. 1, or may be made absolutely moisture proof according to the conditions which it is desired to maintain at the joint.

The band 11, instead of extending only 55 longitudinally along the surface of the part 8 may be simply an ordinary rubber band 13 fitting between the shoulder 12 and the outer end of the part 3 as shown in Fig. 5. In other words, the structure illustrated in 60 Fig. 3 may be modified to the extent of using a band which should be practically cut off at the shoulder 12 and should provide a water-tight joint by means of a flat rubber band between the shoulder 12 and the end of 65 the part 3.

By the use of the soft rubber band, 11, it is possible to secure the advantages of a water tight coupling with different sizes of cables or conductors. For example, the rubber band being inserted between the shoulder 12 and the end of the coupling portion 3 will serve as a water-tight joint even though the outside diameter of the insulation be much smaller than the opening in the ends of the parts 7 and 8. Moreover, assuming 70 that the conductor at one end of the coupling is smaller than the conductor at the opposite end, this would not prevent the use of a standard coupler, inasmuch as the whole structure could be made moisture and water- 75 tight by the insertion of the rubber bushing, as described above.

The rubber band 11 shown in Fig. 3 may be regarded as a washer, although in some instances I prefer to call it a reducer, the 80 shape being similar to that shown in the figure; that is to say, the cylindrical piece of soft rubber with a flange at the end, the cylindrical portion being adapted to lie between the outer circumference of the conductor 85 with its insulated covering and the inner circumference of the part 8 or 7, as the case may be, while the flanged portion rests between the shoulder 12 and the outer end of one of the parts 3. Assuming a sufficiently 90 flexible piece of rubber, this elastic insulating element may be regarded as a reducer, inasmuch as it will fit between the inner portions of the parts 8 or 7, as the case may be, and the outer circumference of conductors 95 of different sizes. Thus, as stated above, the parts 7 and 8 may be made of a standard size while the elastic insulator 11 may be utilized for adapting the said standard parts to internal elements of different sizes. This 100 construction renders the apparatus more easily applicable to different conditions of work and may be used where one size of internal conductor is used at one end of the coupler and another either smaller or greater 105 size is used at the other end.

The rubber band, washer, or reducer 11 may be made of varying thicknesses along the longitudinal portion thereof to still further adapt it to varying sizes of cables or conductors.

I claim as my invention:

1. An insulated coupling for electrical cables or conductors consisting of a metallic coupler comprising two end pieces and an 120 intermediate connecting member having a central portion of larger diameter than the end pieces, in combination with a two-part insulating coupler outside the metallic couplers, the said insulating coupler sections being directly connected one with the other and held from excessive longitudinal movement by the said connecting member.

2. An insulated coupling for cables or conductors having their own external insula- 130

tion, consisting of a metallic coupler comprising two end pieces and an intermediate central portion of larger diameter than the end portions, in combination with a two-part insulating coupler outside the metallic couplers, the said insulating coupler sections being directly connected one with the other and held from excessive longitudinal movement by the said connecting member, and also fitting at their outer ends around the normal insulation of the cables or conductors.

3. An insulated coupling for cables or conductors having their own external insulation, consisting of a metallic coupler comprising two end pieces and an intermediate connecting member having a polygonal central portion of larger diameter than the end portions, in combination with a two-part insulating coupler outside the metallic couplers, the said insulating coupler sections being directly connected one with the other and held from excessive longitudinal movement by the said connecting member and also fitting at their outer ends around the normal insulation of the cables or conductors, and an intervening water-tight packing between the end-pieces and coupler sections.

4. An insulated coupling for cables or conductors having their own external insulation, consisting of a metallic coupler comprising two end pieces and an intermediate connecting member having a central portion of larger diameter than the end pieces, in combination with a two-part insulating

coupler being directly connected one with the other and held from excessive longitudinal movement by the said connecting member, and also provided with shoulders adapted to fit against the ends of the metallic couplers with intervening water-tight joints.

5. An insulated coupling for cables or conductors having their own external insulation, consisting of a metallic coupler comprising two end pieces and an intermediate connecting member having a polysided central portion of larger diameter than that of the end pieces, in combination with a two-part insulating coupler outside the metallic couplers, the two parts of said insulating coupler being directly connected and held from excessive longitudinal movement by the said connecting member, and a cylindrical elastic bushing of insulating material provided with a flange, the cylindrical portion of the bushing being located between the outer circumference of the insulated conductor and the inner circumference of the insulating sheathing, and the flanged portion being located between a shoulder on the said insulating sheathing and the metallic end coupling at each end of the device.

Signed at New York, in the county of New York, and State of New York, this 24th day of February, A. D. 1906.

JOHN J. DOSSETT.
